UNITED STATES PATENT OFFICE.

IRA H. LARR, OF SULLIVAN, INDIANA.

BOAT.

SPECIFICATION forming part of Letters Patent No. 714,805, dated December 2, 1902.

Application filed November 25, 1901. Serial No. 83,633. (No model.)

To all whom it may concern:

Be it known that I, IRA H. LARR, a citizen of the United States, residing at Sullivan, in the county of Sullivan and State of Indiana, 5 have invented a new and useful Boat, of which the following is a specification.

My invention relates to certain improvements in boats or barges used for the transportation of coal, coke, ice, and similar merchandise generally transported in bulk, where a number of such barges are assembled in a fleet and controlled and propelled by a tug or steamer.

In long-distance towing over large bodies of water, where there is plenty of sea room, the various barges are usually connected in a single line, the tug being at the head and the barges connected one to another by long towing-cables and each barge being provided 20 with hand or steam steering-gear to assist in keeping it in the course set by the tug. In such cases but little difficulty is experienced in keeping the barges in the proper course; but in river towing, where the barges are 25 closely connected either by short tow-lines or by direct lashings, much difficulty is experienced in maneuvering the fleet, especially in following the course of a winding stream or in stopping the fleet at a desired point.

30 To overcome these difficulties, I provide specially-constructed barges, which are arranged in a single line and connected closely together in much the same manner as a train of cars are coupled and connected at the forward end to a tug or steamer and at the rear end to a tender provided with steering mechanism and with propelling mechanism having a source of supply independent of the tug or steamer, or being connected to said steamer by conducting wires or pipes for the transmission 35 of electrical energy or for the supply of fluid under pressure.

One of the objects of the invention is to provide for the close connection of the various 45 barges, the steamer, and tender forming the fleet, and a further object is to provide a tender with suitable mechanism to assist in the steering of the fleet and to assist in the gradual checking of its speed prior to a stop, and to 50 provide the tender with propelling apparatus to enable it to tow detached barges from the wharf to the anchorage ground and to assist

in the assembling of the barges when the fleet is forming.

Further objects and advantages of the invention will be apparent from a reading of the following description.

In the accompanying drawings, Figure 1 is a perspective view illustrating a train or fleet of barges connected at one end to a towing-steamer and at the opposite end to a tender or caboose. Fig. 2 is a diagram illustrating a portion of the towing-steamer, a single barge, and a tender constructed and connected together in accordance with my invention 65 and illustrating the general arrangement of the propelling mechanisms and the electrical connections between the source of supply on the steamer and the machinery of the tender. Fig. 3 is a plan view illustrating more clearly 70 the construction of the coupling connections employed between the barges. Fig. 4 is a transverse sectional elevation illustrating the arrangement of the steamer-propelling blades.

Similar numerals of reference are employed 75 to indicate corresponding parts throughout the several figures of the drawings.

The stern of the propelling-steamer 1 and the stern of each of the barges 2 are concaved, as illustrated at 3, and the bow of each of the 80 barges 2 and of the tender 4 are convex, as illustrated at 5. The concaved stern 3 and the convex bows 5 are arranged on correspondingly-curved lines, the bows fitting closely into the sterns of the vessel immediately preceding 85 and being coupled thereto by short lines 6, which may be formed of ropes or of chains, the lines crossing each other, as indicated more clearly in Fig. 3, and extending, respectively, from the port-quarter of the forward 90 vessel to the starboard-bow of the stern vessel and from the port-bow of the stern vessel to the starboard-quarter of the forward vessel. In this manner there is formed a coupling 95 which will permit of the independent pitching of the vessels, but will not permit of any independent sidewise movement. At the same time the connection is such that the vessels may move to follow the course of a bend in the river in the same manner as the 100 cars of a train travel around a curved section of track.

Referring now to the diagram Fig. 2, 8 represents a steam-boiler connected by pipes 9

to engines 10, the latter being connected by suitable gearing 11 to propellers 12, arranged one on each side of the propelling-steamer. If necessary, a single propeller may be arranged at the rear of the steamer by a suitable construction of the hull below the water-line and the deck only being provided with concave portion 3; but such a construction is not desirable in most cases, owing to the effect of the wash on the tow, it being extremely difficult to properly steer a barge connected to a towing-steamer having a single propeller. The arrangement of a propeller at each side of the steamer will produce in a fleet of closely-connected barges a back current or wash on each side of the fleet, which will aid materially in keeping the vessels in alignment. In the steamer there is also arranged an engine 14, connected to one or more dynamos 15, from which extend current-conducting wires 17 to a switchboard 18, and from the latter the current may be directed to a storage battery 19 or to one or more wires 20, having suitable connections to line-wires leading over all of the vessels to the tender 4. The tender is provided with a suitable switchboard 22, from which the current may be directed to a storage battery 23 in order that there may always be a suitable source of power available when the tow is parted. The tender is further provided with an electric motor 24, operatively connected to a propeller 25, arranged at the stern of the tender. The propeller 25 is the reverse of the propeller ordinarily used in steam vessels, the flat or effective surface of the blade being in front of the propeller, while the partially rounded and convex surface is on the rear face. The object of this arrangement is to make the propeller more effective in stopping the fleet and in taking up the slack of the line of barges immediately preceding a stop. If the steamer alone were relied on to stop a long line of barges, the latter could not be kept in the course, the headway being sufficient to cause the barges to move to one side or the other and the steamer losing all control of the fleet as soon as steam is shut off and the engines stop. Each barge is provided with a suitable pipe or tube 26, extending along one or both sides, and at the ends of the barges these pipes are extended toward the center and there connected by flexible couplings 27. In this manner a circuit may be established between the dynamos of the steamer and the motor or storage battery on the tender, care being taken to charge the storage battery 23 of the tender during such times as the motor is not in use. The storage battery 19 of the steamer is employed as a reserve source of power, which may be connected to the motor or the storage battery of the tender in the event of the failure of any of the machinery on the steamer.

65 In assembling a fleet the steamer is connected to one or more barges and then an-

chored in position while the tender tows the remaining barges to position in the line, and after all the barges are assembled and connected the tender is coupled onto the rear end 70 of the fleet or train. The tender is provided with a suitable rudder 30, by which the fleet is steered, and as the series of boats form, in effect, a single vessel formed of a series of hinged sections the wash of the propellers on 75 each side will assist materially in keeping the fleet in proper line. When the fleet is about to stop, the electric motor 24 is set into operation, and owing to the peculiar construction of the blades of the propeller the 80 headway may be effectively checked and the barges kept in proper line until the fleet is anchored. The blades of the propeller 25, while the reverse of those usually employed for the proportions of vessels, are sufficiently 85 effective to enable the tender to take single barges to and from the place of anchorage and to properly assemble the fleet before starting.

It will be understood that the tender may 90 be supplied with a steam or other engine entirely independent of the towing-steamer and that in place of the current-conducting wires the conductor-protecting pipes 26 may be employed to conduct steam or other fluid under 95 pressure from the towing-steamer to an engine on the tender.

Various modifications may be made in the connections between the various vessels and in the form, arrangement, and construction 100 of minor details of the various vessels without departing from the spirit or sacrificing any of the advantages of my invention.

Having thus described my invention, what I claim is—

1. In combination, a fleet of vessels arranged in a continuous but flexible line, a tow-steamer connected to the head of the fleet, a tender connected to the rear end of the fleet, propelling mechanism on the steamer, 110 a power-generator on said steamer, a speed-retarding device on the tender, and power-conveying mechanism extending from the generator to the retarding device on the tender and controllable from the steamer. 115

2. In combination, a series of connected vessels forming a fleet arranged in a continuous but flexible line, a tow-steamer connected to the head of the fleet, a tender connected to the rear end of the fleet, propelling mechanisms on the steamer and the tender, a power-generator on the steamer, a power-storage device on the tender, and power-conveying means connecting the generator the storage device and the propelling mechanisms, thereby permitting the disconnection and independent operation of the tender, substantially as specified. 120

3. In combination, a fleet of vessels arranged in a continuous but flexible line, a tow-steamer connected to the head of the fleet and a tender connected to the stern there-

of, propelling mechanism arranged on the steamer, a dynamo, means for driving the same, a storage battery and wiring connections between the dynamo and storage battery, a storage battery and motor carried by the tender, a reversed propeller arranged at the stern of the tender and adapted to be operated by the motor, and current-conducting wires carried by the various vessels and con-

nected to form a continuous circuit between the steamer and tender.

In testimony that I claim the foregoing as my own I have hereto affixed my signature in the presence of two witnesses.

IRA H. LARR.
